UNITED STATES PATENT OFFICE.

AUGUSTUS C. CAREY, OF BOSTON, MASSACHUSETTS.

ELECTRIC REGULATOR.

No. 843,733.

Specification of Letters Patent.

Patented Feb. 12, 1907.

Application filed July 15, 1904. Serial No. 216,695.

To all whom it may concern:

Be it known that I, AUGUSTUS C. CAREY, a citizen of the United States, residing at Boston, in the county of Suffolk and State of Massachusetts, have invented a certain new and useful Improvement in Electric Regulators, of which the following is a full, clear, and exact description.

The object of this invention is to provide a device by means of which the application and control of an electric current may be regulated in an inexpensive manner, the device being capable of use both as a regulator and as a receiver.

The invention comprises, fundamentally, a tube of glass or other insulating material containing loose particles of conductive material therein and arranged between conductive plungers, one or both of which may be adjusted in order to collect the loose particles into a more or less compact mass. Either or both of these plungers may be wound with insulated wire to form electromagnets or inductoriums.

In the accompanying drawings, illustrating the invention, in the several figures of which like parts are similarly designated, Figure 1 is a plan view with part of an optionally-employed shield broken away. Fig.

2 is a longitudinal section showing a variation in the arrangement of the plungers. Fig. 3 is a longitudinal section showing another variation in the arrangement of the plungers.

The base 1 may be of any form and material, and in Fig. 1 it is shown as of wood, having bearing-blocks 2, in which is supported a tube 3, of glass or other insulating or electrically non-conductive material. In this tube is placed a quantity of loose particles 4 of electrically-conductive material—such as brass, steel, silver, or other alloy or metal—confined between plungers 5 and 6 of equal or unequal length, one or both of them being capable of adjustment lengthwise of the tube in order to move the loose particles into a more or less compact mass, and thereby form a more or less efficient conductor of electricity.

In Fig. 1 the plunger 5 is supposed to be stationary and shorter than plunger 6, and the plunger 6 is shown adjustable by means of a toothed rack-bar 7, engaged by a pinion 8, operated by a key 9. The rack-bar has its outer end supported in a bracket 10, and this bracket may be supplied with a pointer 11,

coöperating with graduations 12 on the rack-bar to indicate the extent of movement of the plunger and the consequent degree of compacting thereby resulting upon the loose particles to prepare them for currents coming from greater or less distances or currents of more or less strength. As shown in Fig. 1, the plungers may be composed of rods of considerably smaller diameter than the bore of the tube, and these rods may be supplied with one or more disks of substantially the diameter of the tube; but in any case the ends of the plungers, which coöperate with the mass of loose particles, must be of sufficiently close fit with the interior of the bore of the tube to prevent the escape of the particles past them. The plungers may be wound with the same or different lengths of insulated wire 13. As shown in Fig. 1, the wire is alike upon both plungers and may be applied to form an electromagnet or an inductorium, or, as shown in Fig. 2, one plunger may be an electromagnet and the other an inductorium, or, as shown in Fig. 3, one plunger may be left plain and the other be an electromagnet or an inductorium. Other variations in the arrangement of these plungers may be used in carrying out the purposes of the invention.

The plunger rods and disks are constructed of soft iron or other good conducting or magnetic material, and either or both of said rods may be wound between the disks with insulated wire to form electromagnets or inductoriums. In the preferred construction the leading-in terminal of the winding is passed through the outer disk of the plunger and is carried outside of the tube 3 in any suitable manner to be connected with one of the terminals of the circuit in which the device is to be used, and the other terminal of the winding is electrically connected with the inner disk of the plunger.

If it be desired to form inductoriums of the plunger-rods, the rods are wound between the disks, as is usual in inductorium constructions, both the terminals of the secondary winding being electrically connected with the inner disk. If both plungers are constructed as electromagnets or inductoriums, the windings are arranged reversely and the leading-in wires of the windings are connected to the terminals of the circuit in which the device is to be used, and the current passes through the windings of the electromagnets and from the magnets or plungers through the loose particles. The

current passing through the windings energizes the plungers or cores of the magnets, and thus produces a magnetic field between the inner ends of the plungers or disks, and such magnetic force destroys or prevents any 5 arcing or sparking of the current as it passes through the loose particles, and thus maintains the continuity or regularity of the current as it passes through the device. The 10 same effect will be produced by forming only one of the plungers as an electromagnet, as shown in Fig. 3, and in this case the terminals of the circuit in which the device is to be used are connected, respectively, with the 15 leading-in terminal of the winding of the electromagnet upon one side of the device and with the outer end of the plunger upon the opposite side of the device.

When the device is used as a regulator, the 20 longer plunger or rod is drawn back or away from the other, leaving the loose particles piled up against the opposite plunger, and then by moving the longer plunger toward the shorter one the particles that may have fallen away are gathered into more or less intimate contact. When, however, the device is to be used as a receiver or coherer, the 25 plungers are brought into sufficiently intimate contact to compact the loose particles 30 as closely as possible in order to make the most perfect and extensive conductor. Should the particles remain compacted when it is desired to have them fall away, they 35 may be separated by tapping the tube by hand or by an instrument supplied for that purpose.

By the use of a rack and pinion for adjusting the plunger the plunger may be adjusted by variable movements or with more or less 40 rapidity in order to effect the proper adjustment of the loose particles within the tube in accordance with the requirements of the circuit in which the device is used—that is to say, the plunger may be adjusted with a slow 45 movement to effect a gradual compacting or loosening of the particles, or with a quick movement to effect a practically instantaneous compacting or loosening of the particles. In order to protect the tube from

breakage, it may be covered by a shield 14 of 50 metal or other material, as shown in Fig. 1.

What I claim is—

1. The combination of an electrically-non-conductive tube, a mass of loose particles of electrically-conductive material arranged 55 therein, and electrically-conductive wire-wound plungers arranged in said tube and between which the loose particles are more or less intimately confined.

2. The combination of an electrically-non-conductive tube, a mass of loose particles of electrically-conductive material arranged 60 therein, and electromagnetic plungers arranged in said tube and between which the loose particles are more or less intimately 65 confined.

3. The combination of an electrically-non-conductive tube, a mass of loose particles of electrically-conductive material arranged 70 therein, and plungers arranged in said tube, and between which the loose particles are more or less intimately confined, one of said 75 plungers being an electromagnet or inductorium.

4. The combination of a non-conductive 80 tube, a mass of loose particles of conductive material arranged therein, electromagnetic plungers arranged in said tube on opposite sides of said mass, and means for adjusting said plungers to vary the compactness of the 85 loose particles.

5. The combination of a non-conductive tube, a mass of loose particles of conductive material arranged therein, electromagnetic plungers arranged in said tube on opposite 90 sides of said mass, one of said plungers having a rack, a pinion co-operating with said rack for adjusting said plunger to vary the compactness of the loose particles, and an indicating mechanism for determining the effective movement of the plunger.

In testimony whereof I have hereunto set my hand this 4th day of July, A. D. 1904.

AUGUSTUS C. CAREY.
